174,517

CAP OR SIMILAR ARTICLE

Herman Schwartz, San Francisco, Calif.

Application July 27, 1954, Serial No. 31,633

Term of patent 3½ years

(Cl. D3—13)

To all whom it may concern:

Be it known that I, Herman Schwartz, a citizen of the United States of America, residing in the city and county of San Francisco and State of California, have invented a new, original, and ornamental Design for a Cap or Similar Article, of which the following is a specification, reference being had to the accompanying drawing, forming part thereof.

I claim:

The ornamental design for a cap or similar article, as shown.
